UNITED STATES PATENT OFFICE.

GEORGE R. BLAKESLEY, OF EDGERTON, WISCONSIN.

ELECTRIC WATER HEATER.

Application filed December 4, 1920. Serial No. 428,212.

To all whom it may concern:

Be it known that I, GEORGE R. BLAKESLEY, a citizen of the United States, and a resident of the city of Edgerton, in the county 5 of Rock and State of Wisconsin, have invented certain new and useful Improvements in an Electric Water Heater; and I do hereby declare that the following is a full, clear, and exact description of the same, 10 reference being had to the accompanying drawings, and to the numerals of reference marked thereon, which form a part of this specification.

My invention relates to a heating apparatus for water in which water is passed over an electrically heated coil or device, and in which the electric current is controlled by the flow of the water.

It is therefore an object of this invention 20 to provide a simple electric water heater in which the electric current is turned on by the flow of the water and turned off when the flow of the water is stopped.

It is also an object of this invention to 25 provide a novel heating device that comes into contact with most of the water that flows thereover.

Other and further important objects of 30 this invention will be apparent from the disclosures in the specification and drawings.

The invention (in a preferred form) is illustrated in the drawings and hereinafter more fully described.

35 In the drawings:

Figure 1 is a top plan view of a pipe or cylinder used in connection with my invention, with the cover removed.

Figure 2 is a section on the line 2—2 of 40 Figure 1.

Figure 3 is a section on the line 3—3 of Figure 2.

Figure 4 is a section on the line 4—4 of Figure 2.

45 As shown on the drawings:

In the different figures of the drawing, similar features are denoted by similar reference numerals.

For the purpose of illustrating my invention, I have shown a hollow cylindrical member 1, which may be a pipe, a cylinder or any similar structure made of insulating material, through which water can flow. In one end of said member, I provide an enlarged bore having the beveled annular shoulder 2, against which the beveled end

of a spiral heating device 3 is designed to abut. In the outer end of said member, I preferably secure a removable hollow section 4 having an annular beveled shoulder 60 5 to contact with the outer beveled end of the heating device or element 3 to properly secure the same in place. The hollow section 4 may be screw-threaded within the water containing member 1 so as to provide 65 an adjustable abutment for the heating device.

While the heating device 3 may itself be an electrical conductor of high resistance, I preferably employ an electrical resistance 70 which may consist of an insulated coil of wire 3^a wrapped around the spiral element and connected at one end with a contact 6 in an insulated plug 7 in the water pipe 1 and connected at the other end with a like 75 contact 8 in an insulated plug 9. Thus the electrical current from some convenient source can enter through one contact, traverse the coil and heat the same and likewise the spiral element and emerge at the other 80 contact.

In order to control the current leading to the contact 6 which may be assumed as the positive one, a switch mechanism is provided, and as shown, this switch mechanism 85 comprises a stationary switch contact plate 10 supported by a conductor 11 secured on the plug 7 by means of the contact screw 6 with which the conductor is in engagement. The movable contact member comprises a 90 segmental plate 18 pivoted at 12^a and having an upwardly projecting pin 19 engageable with the end walls of an arcuate slot 13 in a superposed plate 12 pivoted at 12^a and effective to normally withdraw the movable 95 contact 18 into inoperative position by means of a coil spring 14 surrounding a link 15 connected with said plate 12 and passing through an aperture in the flange 16 rising from the water container 1; the 100 spring 14 being confined under certain compression between the wall 16 and an abutment 17 near the end of the link member.

A coil tension spring 22 secured on a lug 105 23 beyond the casing and extending through a slot in the casing is connected to the pin 19. The lug 23 and pivot 12^a are spaced apart in the same transverse vertical plane passing through the water pipe and at right 110 angles thereto. It is therefore apparent that as soon as pin 19 is shifted slightly to

either side of the said vertical plane, the spring 22 will become effective to snap the movable contact.

The movable contact member 18 is provided with a conductor 20 extending through a slot in the casing which may be made sufficiently rigid if desirable to serve as a handle for manual operation of the switch. The current may enter through the conductor 20 and if the switch is closed, traverse the same and enter the heater through the contact 6 and emerge at contact 8.

The switch is preferably rendered automatic by means of the springs and the force of the inflowing water. This is effected by connecting the link 15 with the water valve 24 which has a stem 25 projecting through an extension 26 of member 1 and into the casing in the plane of the link 15, the connection being made by a crank 27 firmly secured on the valve stem, and a link 28 is loosely pivoted to the crank and the link 15. The construction is such that the inflowing water will open the valve 24 and turn the crank 27 so that the link 15 will be shifted to the right against the tension of the spring 14, thus moving the member 12 toward the right. The pin 19 will be constrained to move with the member 12 and when the same passes the aforementioned vertical plane, the spring 22 will become effective to shift or aid in shifting the movable switch member 18 into closed position into contact with the stationary switch plate 10.

The cylinder or pipe member 1 may be connected with an inlet pipe 29 coupled with the extension 26 and the flow of water through the inlet pipe may be controlled by a faucet. Thus by opening the faucet, the water will flow through the extension 26 and force the valve 24 open against the tension of the spring 14, which is designed to be sufficiently weak to be overcome by the force of the water, and the switch will be closed as above explained. And when the faucet is closed, relieving thereby the water pressure on the valve, the spring 14 will become effective to draw the member 12 toward the left. The pin 19, being at this time in the right hand end of the slot 13, will be constrained to travel with the member 12 until a point just to the left of the previously described vertical plane is reached, when spring 22 becomes effective to snap or assist in snapping the movable contact member 18 into the position shown in Figure 1. It will hence be observed that the tension of spring 14 need not be any greater than is required to draw the pin 19 a little to the left of the said

vertical plane, and it hence can be made sufficiently weak so as to be overcome by the inflowing water.

The pipe section 32 may lead to a bath tub, shower, sink or to any point where hot water is desired, and in case where the pipe member 1 is exposed, the switch mechanism may be enclosed by the casing 21 which encloses the mechanism from four sides as shown in Figure 1, and a cover 30 may be provided to close the top of the casing.

It is characteristic of my invention that the water traverses in a spiral course around the member 3, and directly in contact with the heat producing medium which is illustrated as consisting of the above described high resistance wires. It will thus be evident that the spiral course will keep the water in contact with the heat producing medium for a longer period than if a straight course were pursued, and further in following this spiral course, the water will be agitated so that most of it will come directly in contact with the heated wires. These are important features of my apparatus and produce far better results than the externally wire wrapped pipes now on the market.

It will according be observed that my device is automatically regulated in a novel way and that the heating device is designed to give the most efficient results and that by having the water traverse a circuitous or spiral course, it remains longer in contact with the heat producing medium.

I am aware that numerous details of construction may be varied through a wide range without departing from the principles of this invention, and I therefore do not purpose limiting the patent granted otherwise necessitated by the prior art.

I claim as my invention:

In an automatic control for an electrical water heater, means for controlling the electric current comprising a stationary contact member, a pivoted contact member having a stud projecting therefrom, a pivoted actuator having an arcuate slot for receiving said stud, a spring connected to said stud for alternately actuating said movable contact member to open or closed position, a spring actuated rod attached to said actuator for oscillating the same, and a flap valve connected to said rod and operable for shifting said rod for moving said movable contact member toward closed position.

In testimony whereof I have hereunto subscribed my name.

GEORGE R. BLAKESLEY.
